UNITED STATES PATENT OFFICE.

KARL KIEFER, OF CINCINNATI, OHIO.

FILLING APPARATUS.

1,164,360.

Specification of Letters Patent. Patented Dec. 14, 1915.

Application filed December 18, 1911, Serial No. 666,470. Renewed October 18, 1915. Serial No. 56,593.

To all whom it may concern:

Be it known that I, KARL KIEFER, a citizen of the United States, residing at Cincinnati, in the county of Hamilton and State of Ohio, have invented certain new and useful Improvements in Filling Apparatus, of which the following is a specification.

My invention relates to filling machines, and its object is to provide simple and effective means for governing the filling height.

My invention consists in the novel details, and in their combination and embodiment in the filling tube of a filling machine, as will hereinafter be more fully described and claimed.

In the drawings: Figure 1 is a vertical sectional elevation of a filling tube embodying my improvements, the tube and its parts being in section, and part of a filling tank, in elevation, being also shown. Fig. 2 is a detail plan view of the top of the filling tube mounting. Fig. 3 is a sectional elevation of part of the filling tube of Fig. 1, inserted into a bottle. Figs. 4 and 5 are partial elevations of the filling tube of Fig. 1, showing different adjustments thereof. Fig. 6 illustrates a series of pins used in the different adjustments shown in Figs. 1, 4 and 5. Fig. 7 is a vertical section of a modified filling tube embodying some of the details of my invention. Fig. 8 is a detail elevation of the gasket. Fig. 9 is a similar view of the lower member of the gasket-supporting stop. Fig. 10 is a detail plan view of the upper member of said gland. Fig. 11 is a similar view of the collar. Fig. 12 is a sectional side elevation, illustrating a modification of the adjustment device. Fig. 13 is an elevation of another modification of the filling tube, with its mounting, the adjustment device being also modified. Fig. 14 is an inverted plan view of the stop used in the modification illustrated in Fig. 13.

In the device illustrated in Figs. 1 to 3, and also used as the example in Figs. 4 and 5, there is the combination of a filling tube with the valve in its free end, or tip, and means for closing the mouth of the bottle or other vessel against the outer air, when the tube is inserted for operation.

The valve in the tip of the tube is, preferably, as shown, of the construction set forth in my co-pending application filed De-

cember 18, 1909, Serial No. 533,934, with an annular valve seat engaging the slidable sleeve and a flexible washer supporting the valve seat. Such a valve has been generally used by me in connection with a machine wherein the mouth of the vessel is left open during the filling, as in the example of Figs. 13 and 14 in this specification; in such machines, no particularly heavy pressure is needed in pressing the stop against the vessel. Under such conditions, the valve above alluded to suffered no particular damage from the pressure of the comparatively light spring employed.

In the example of Figs. 1 to 5, however, I have found that the strong spring that is needed to press the gasket against the bottle-top will, if also allowed to seat the valve in the tip of the tube, impose too much pressure on this valve, so that it is damaged and its effectiveness impaired in a short time. The metal valve seat, as well as the rubber washer that supports the seat, are, as is evident, both necessarily delicate, since their dimensions are limited to the small space allowable at the tip of the tube, which must be inserted into bottle-necks of small caliber.

I avoid the difficulties above pointed out by providing a strong spring that seats the gasket on the bottle-top, and providing a second weaker spring to seat the valve in the tip of the tube. Thus, in Figs. 1 and 2, the tube 1 corresponds in function to the sleeve of my other application above referred to, and the inner tube of said application is here represented by a short tube or cup 2, rigidly attached to a longer tube or vent 3, of less diameter, and running up through the tube 1, above the upper end of which it is supported by the weaker spring, and thus supports the cup 2. This cup 2 fits slidably in the tube 1, so that the tube 1 guides the cup 2, and the lower end of the vent 3. As shown, the vent 3 is eccentric to the cup and to the tube 1 in its lower region, being secured to one side of said cup at its lower end, as by soldering, so as to be practically integral therewith.

The cup 2 has a lateral orifice 2' in its side opposite the vent 3, and two smaller orifices 3' are provided, one above the other through the attached walls of the cup and vent. A plurality of smaller orifices is provided, rather than a single larger one, so that early opening of the vent will occur.

An elongated slot would be equivalent, but not so economically formed. Preferably, the orifice 2' of the cup is located somewhat higher than are the orifices 3'.

5 The lower end of the cup 2 is closed and has a downwardly extending threaded stud 2^a, around which is the annular, valve seat 2^b and the flexible washer 2^c, and upon which is screwed the nut 2^d to support said washer and seat; the nut 2^d is tapered, and forms the guiding tip of the tube. Other or additional guiding means may be provided to insure the insertion of the tube into the bottle-neck, but need not be set forth herein.

10 The upper end of the tube 1 is rigidly attached centrally in a hub 1^a which slides in a head 4 and makes guiding contact with the inner walls of the chamber 4^a formed in said head, said hub having a flange 1^{a'} at its upper end to make such contact, but not to form a liquid-tight connection with said walls of the chamber. As shown, the upper end of the tube 1 is flush with the upper end of this hub 1^a.

15 Slightly below the lower end of the hub 1^a, the tube has lateral orifices 1^b, and the chamber 4^a receives said lower end of the hub 1^a on its bottom 4^{a'}, so that the tube is stopped from further downward movement by this engagement, with its lateral orifices 1^b below the bottom 4^{a'} and inclosed by the closely fitting walls of the tube passage 4^b which the head has below its chamber 4^a. 20 This tube passage 4^b is closed against leakage around the tube 1 by a gland 4^c in its lower end.

25 Immediately above its bottom, the chamber 4 has the lateral inlet orifice 4^a, to which a supply pipe 5 extends horizontally from the filling tank 6. This filling tank may be constructed with a float 6^a that may control a valve 6^b to maintain a practically unvarying level of the liquid in the tank.

30 The upper end of the vent 3 is rigidly attached to a guide 3^a which has a lateral orifice 3^{a'} from the vent into the chamber 4^a. The lower end of this guide 3^a is far enough above the upper end of the tube 1 to allow upward sliding of the tube to expose the orifices 1^b for direct communication with the inlet orifice 4^a; also, the entire chamber is positioned in such relation to the tank 6 and its float 6^a that the orifice 3^{a'} of the vent guide will be considerably above the level of the liquid in the tank 6, and, consequently, of the liquid in the chamber 4^a, since the tank and chamber communicate through the tube 5.

35 For guiding the upper end of the vent 3, the head 4 has a cap 4^c over the chamber 4^a, with a central opening 4^{c'} in which the guide 3^a of the vent slides. A screw 3^b enters the upper end of the guide 3^a and compresses a helical spring 3^a, around the upper part of

the guide, down against the cap 4^c; this is the weaker spring hereinbefore alluded to. The cap 4^c has other openings 4^{c''}, leaving the chamber 4^a open to the atmosphere. Below the cap 4^c, the guide 3^a has a transverse pin 3^e, engaging the cap to allow only a slight vertical upward movement of the vent 3, with attached cup 2 and valve parts, as pressed by the spring 3^a, when the tube 1 is raised. To prevent turning of the vent 75 and of the valve parts supported thereby, the guide 3^a of the vent, and the opening 4^{c'} in the cap 4^c, through which the guide slides, are made square.

40 A collar 1^e is secured on the outside of the tube 1, and a helical spring 1^d, around the tube, is compressed between this collar and the lower side of the gland 4^c in the lower end of the head 4. This spring thus presses the tube 1 down until stopped by the engagement of the hub 1^a with the bottom of the chamber, as before mentioned. The collar 1^e is split at one side and a screw 1^f draws it together, so that it may be clamped on the tube at any point and thus adjust 90 the pressure of the spring 1^d on the tube. Turning of the tube 1 is prevented by a parallel guide 1^g, extending down from a lateral extension of the lower end of the head 4, the collar 1^e on the tube having an 95 extension 1^{g'} that slides on this guide 1^g.

45 By preventing turning of the vent 3 and attached parts, as well as of the tube 1, the seating of the valve in the tip of the tube is maintained uniform, so that it will remain 100 more efficient.

The gasket 7 that makes tight connection with the top of the vessel, as best shown in Fig. 2, is supported by a stop 8, comprising, as shown, a lower body 8^a and an upper gland 8^b, tightly compressing a suitable packing 8^c around the tube 1. The body 8^a has a downwardly extended sleeve 8^{a'}, fitting the tube snugly, upon which the gasket 7 is held by its own elasticity. This sleeve 110 8^{a'} is made thin, so that the gasket surface approaches the tube closely, as required. As shown, the gasket 7 has a flat side and a convex side, and the flat side is presented downwardly; it may be reversed. In either 115 case, the gasket, which may be of soft rubber, will yield to any unevenness of the top of the vessel, and thus effectually close the connection thereat against the outer air, and against leakage of the liquid entering the 120 vessel from the filling apparatus.

50 By mounting the gasket 7 on the sleeve 8^{a'} of the stop 8, and having the stop releasable from the tube by unscrewing its members, movement of the parts on the tube, to provide different adjustments of the filling height, is facilitated more than where it is necessary to slide the gasket itself on the tube; at the same time the gasket makes tight connection with the sleeve and adja- 125 130

cent parts of the stop, and the stop, when tightened, makes connection with the tube.

The tightening of the stop 8, pressing the packing 8^c against the tube, however, is not adequate to provide a positive support against sliding of the stop and the gasket on the tube, under the somewhat heavy pressure that the spring 1^d opposes to the raising of the tube, as is necessary to afford the tight connection with the top of the vessel.

To provide such positive support, without complication, I provide a pin 9 to stand parallel with the tube 1 and enter a socket 8^b in the upper side of the gland 8^b of the stop 8, and to enter a socket 1^c in the lower side of the collar 1^c. By providing other pins, of different lengths, as the pins 9' and 9'', in Figs. 4 and 5, respectively, suitable adjustments of the stop 8 and gasket 7 may be made, and these parts positively maintained in such adjustments against the pressure of the spring 1^d. A group of these assorted pins is shown in Fig. 6; it will be understood that any desired number of these pins may be provided for each filling tube, varying in length by any desired amounts, to secure the full number of adjustments required for the different vessels to be filled.

By having the strong spring 1^d to resist the rise of the tube 1, but opposing the vent 3, with attached parts, to the weak spring 3^d only, it will be seen that, as the tube 1 starts upward on engagement of the vessel with the gasket 7, the valve seat on the cup 2 and vent 3 will follow, as pulled up by the weaker spring 3^d, until the pin 3^e engages to stop this upward movement; then the tube 1 will continue upward, exposing its orifices 1^b in the chamber, above, and exposing the orifices 2' and 3', of the cup and vent, below. Liquid will now flow from the tank 6, through the tube 1, into the cup 2, and into the vessel through the orifice 2', and the air that was in the vessel will escape through the vent 3 and out through the open top of the chamber 4^a, above. This continues until the liquid level in the vessel reaches the orifices 3', closing them against further escape of air, upon which liquid will pass up into the vent through these orifices, filling it to the level of the liquid in the tank 6; when this level has been reached, all flow of liquid will cease, and the vessel may be removed. When the next vessel is applied to the tube, the exposure of the vent orifices 3' will allow down-flow of the liquid that had entered the vent 3, until such flow is balanced by air pressure accumulated in the bottle under action of

the main flow from the orifice 2', which began immediately after the flow from the vent began, or rising of the tube 1. Then, this excess of pressure of the air over that of the down-flow from the vent will result in reversal of the flow in the vent, and the

liquid will be forced out of the upper end of the vent, into the chamber 4^a, mingling with the main current of liquid flowing therethrough from the tank.

From the above description of the operation of this particular form of filling apparatus illustrated in Figs. 1 to 5, it will be seen that my improvements greatly facilitate the operation of devices of this character, where it is desired to avail of a closed bottle-top along with a filling tube with a valve in its tip.

The positive adjustment afforded by the pins combined with the stop and collar is also of advantage in other forms of apparatus, as in those illustrated in Figs. 7 and 13.

The tube 11 of Fig. 7 has its valve 11^a in its upper end and has suitable means 12 in its lower end, or tip, acting by capillarity, to hold liquid suspended in the tube on removal of the vessel. A vent 13 opens laterally through the tube 11, immediately above the capillary liquid-suspension tubes 12 provided in the end of the tube to prevent dripping and extends up inside the tube, at one side thereof, to a point near the upper end, where it again opens through the side of the tube. The tube has a hub 11^b that forms a shoulder around the tube immediately above the upper vent opening, constituting a valve 11^c seating on the bottom of the chamber 14, in which chamber the tube slides. This chamber has a lateral overflow orifice 14' shortly above the seat of the valve 11^c, and rising of the tube may allow direct communication of the vent 13 with this overflow orifice. The upper part of the chamber 14 is enlarged, and the valve 11^a of the tube 11 is seated on a seat 11^a' resting on the bottom of the enlarged part of the chamber. This enlarged part of the chamber has a lateral supply orifice 15 leading from the reservoir 16, and the upper end of the chamber is closed by a plug 14^a. The lower end of the chamber has a gland 14^b around the tube 11.

The gasket 7 with its stop 8, identical with that before illustrated and described, is held by the pin 19 in proper spaced relation with the collar 11^c, which is like the collar 1^c before shown, except that the extension 1^c is omitted, no guide for the tube, other than its mounting in the chamber 14, being provided. This collar 11^c compresses the spring 11^d up against the gland 14^b, being tightened by a screw 11^e and having a socket 11^c to receive the upper end of the pin 19.

Pressure of the bottle-top on the gasket raises the tube; the liquid flows through the tube into the bottle until its level reaches the lower vent opening; then further flow of liquid is through the vent, and through the overflow orifice, from which it is con-

ducted to a proper receptacle through an overflow pipe 14^c. Such a receptacle may be one of the bottles next to be filled.

In the modification illustrated in Fig. 12, the tube 21 has the collar 21^c with the screw 21^c and socket 21^c, like that of the previous examples, and a spring 21^d bears on this collar. The stop 28, however, comprises a lower body 28^a and upper gland 28^b, with sleeve 28^c for the gasket 7, and with socket 28^d for the lower end of the pin 29, respectively. The telescoping parts of these members are smooth, and they compress the packing 28^e by being drawn together by two screws 28^f, flanking the tube 21 and parallel thereto.

In Fig. 13, the tube has the valve at its tip as in Figs. 1 to 5.

This device is used on filling machines operating by syphonic action, in which the flow of liquid stops when the liquid in the vessel reaches the level of the liquid in the supply reservoir, and therefore does not require tight connection with the bottle top; on the other hand, open communication from the interior of the vessel to the outer air is required at the top of the vessel. In this device, the lower end of the inner tube 31 is closed and solid, supporting the valve seat 31^b and its flexible washer by the nut 31^c, being, in this respect, the equivalent of the cup 2 of Figs. 1 to 5. The inner tube 31 has the lateral discharge orifice 31^d, and the lower end of the outer tube 32 closes this orifice 35 when it seats on the valve seat 31^b. The upper end of the outer tube has a head 32^a, carrying a frame 32^b, and this frame arches over the pivotal mounting 33 of the inner tube 31. A spring 32^c stretches from the arch of the frame to this mounting, thus drawing the outer tube 32 down so that its lower end seats on the valve seat, as before mentioned. This spring 32^c need not be strong, under the conditions in this case, and may exert its full pressure on the valve parts without damaging them. Relative turning of the inner and outer tubes is prevented by providing the pivoted pin 33^a of the mounting 33 with a notch 33^b that receives the side of the frame 32^b, thus relieving the valve in the end of the tube of the effects of relative shifting of its engaging parts, as was before alluded to in connection with the description of the device shown in Figs. 1 to 5.

The stop 34, corresponding to the gasket and stop of the preceding examples, is split at one side, with a transverse screw 34^a drawing it together and clamping it on the outer tube, similar to the collar of the previous examples. However, the member that corresponds to the collar here, is the head 32^a of the outer tube. It receives the tension of the spring 32^c and transmits it to the outer tube, and it is between it and the stop 34 that the

pin 39 is interposed. This pin 39 fits a socket 34^b in the upper side of the stop 34, but as here shown, there is no socket in the under side of the head 32^a, the pin merely engaging at random with this under side. 70

The lower side of the stop 34 has radial grooves 34^c, venting the engagement of the stop with the bottle-top, under the requirements above mentioned. With a small bottle, even with a small tube, the projection of the 75 tube below the liquid level may be in bulk equal to a considerable proportion of the capacity of the bottle, whereupon this bulk must be lessened by raising the tube with respect to the liquid level. With a larger 80 bottle, where the bulk of the tube is not so significant, the tube not only may be larger, but may be lowered so that the advantage of rapid outflow results, from increasing the distance of the outlet below the level of liquid supply. The stop 34 is used for this purpose. The action being syphonic, no overflow need be provided for. Such apparatus is fully described in my Patent No. 863,395, dated September 10, 1907, as well as in my 90 co-pending application hereinbefore referred to.

The novel adjusting device herein set forth, it will be seen, is applicable to the various devices illustrated as examples; and 95 the combination embraced in Figs. 1 to 5 is especially applicable to a rotary machine; as that of my co-pending application above referred to, or to the power-driven rotary machine set forth in my Patent No. 1,017,418, 100 dated February 13, 1912.

Having fully described my invention, what I claim as new and desire to secure by Letters Patent is:

1. In filling apparatus, a tube, a valve seat 105 engaging with the end of the tube, a head in which the tube is slidable, a vent extending from the valve seat through the tube and into said head, a guide for the tube supported in the head parallel to the tube, and a projection from the tube engaging with the guide, said guide preventing turning of the tube relative to the valve seat.

2. In filling apparatus, telescoping members, the inner one of which has a hollow interior with closed end and lateral orifice, and the outer one sliding over the orifice, an annular valve seat surrounding the closed end of the inner member to engage with the end of the outer member, a flexible mounting for 115 the valve seat, and means for preventing relative turning of the members during relative sliding thereof.

3. In filling apparatus, an inner cup with closed end and lateral orifice, a vent tube 125 rigid with the cup, said vent tube and cup having an orifice through their walls in common, an outer tube sliding over said orifice, a stud on the closed end of the cup, an annular valve seat around the stud engaging with 130

- the end of the outer tube, a flexible washer supporting the valve seat, a nut on the stud supporting the washer, and means for preventing the turning of the cup and said parts supported thereby, and of said outer tube, during the sliding of the tube.
4. In filling apparatus, a tube, a valve seat engaging with the end of the tube, a vent rigidly connected to the valve seat, a guide for the vent of angular cross-section, said vent comprising means which coöperate with said guide of angular cross section to prevent the turning of the vent with the valve seat, a spring moving the vent, and with it the valve seat and the guide, and a transverse pin in the guide to stop the movement caused by said spring.
5. In filling apparatus, a tube, a valve seat engaging with the end of the tube, a stop on the tube through which engagement of a vessel moves the tube to disengage the end of the tube from the valve seat, a spring pressing the tube toward the valve seat, a stop to limit the movement of the tube as pressed by said spring, a second spring pressing the valve seat toward the end of the tube in opposition to the aforesaid spring, and a stop for the valve seat, limiting its movement as pressed by said second spring.
6. In filling apparatus, a tube, a valve seat engaging with the end of the tube, a spring pressing the tube toward the valve seat, a stop for the tube under such pressure, and a spring supporting the valve seat against the end of the tube.
7. In filling apparatus, a tube, a valve seat engaging with the end of the tube, a spring pressing the tube toward the valve seat, a stop for the tube under such pressure, a spring supporting the valve against the end of the tube and causing it to follow the tube on movement of the tube away from it, and a stop to limit such following of the valve seat.
8. In filling apparatus, a tube, a valve seat engaging the end of the tube, a stop on the tube and a gasket on the stop to engage with a vessel in which the tube is inserted, a spring to cause pressure of the gasket on the vessel, a second spring to cause pressure of the valve seat on the end of the tube, and also to cause the valve seat to follow the tube on movement of the tube away from it, and stops to limit the movements of said tube and said valve seat under the pressures of their respective springs.
9. In filling apparatus, a tube, a valve seat engaging with the end of the tube, means for causing the engagement of the valve seat with the end of the tube, a stop tightened on the tube, a gasket carried by the stop for engagement with a vessel into which the tube is inserted, a collar tightened on the tube, a spring engaging the collar to cause pressure of the gasket on the vessel,

and a removable pin between the collar and said stop, to transmit said pressure from the spring to the gasket.

10. In filling apparatus, a tube, a gasket thereon to engage a vessel into which the tube is inserted, a spring to press the gasket against the vessel, and spacing means between the gasket and the spring, transmitting said pressure, and removable without removing the gasket from the tube. 75

11. In filling apparatus, a tube, a gasket, supporting means on the tube for the gasket, a spring to press the gasket against a vessel into which the tube is inserted, supporting means on the tube for said spring, 80 and spacing means between the respective supporting means, and removable without removing the gasket from the tube.

12. In filling apparatus, a tube, a gasket, releasable supporting means on the tube for 85 the gasket, a spring to press the gasket against a vessel into which the tube is inserted, releasable supporting means on the tube for the spring, and spacing means between the respective supporting means, and 90 removable without removing the gasket from the tube.

13. In filling apparatus, a tube, a gasket, a stop supporting the gasket and adjustable along the tube, a collar, secured on the tube, 95 and a pin spacing the stop from the collar and adapted to be removed or replaced without removing the stop or gasket from the tube.

14. In filling apparatus, a tube, a stop 100 comprising opposed co-acting members, a packing compressed around the tube by said members, a collar secured on the tube, and a pin engaging said collar and one of the members of the stop. 105

15. In filling apparatus, a tube, a stop comprising opposed co-acting members, a packing compressed around the tube by said members, a collar secured on the tube, said collar and one of the members of the stop 110 having sockets, and a pin engaging within the sockets and spacing the stop from the collar.

16. In filling apparatus, a tube, a stop comprising opposed co-acting members, a 115 packing compressed around the tube by said members, a sleeve extending from one of the members around the tube, a gasket on the sleeve against said member of the stop, the other member of the stop having a socket, 120 a collar secured to the tube and also having a socket, and a pin engaging within the sockets and spacing the stop from the collar.

17. In filling apparatus, a tube, a gasket, packing means supporting the gasket on the 125 tube, a spring resisted by said packing means, and spacing means between the packing means and the spring, removable without removing the packing means from the tube. 130

18. In filling apparatus, a tube, a stop on the tube to engage with a vessel, a spring to resist the stop, and engaging and spacing means transmitting the pressure of the 5 spring to said stop, removable without removing the stop from the tube.
19. In filling apparatus, a tube, a stop on the tube, a projection secured to the tube, and spacing means between the stop and 10 the projection, removable without removing the stop from the tube.
20. In filling apparatus, a tube, a stop releasably secured on the tube, a projection secured to the tube, and spacing means 15 between the stop and the projection, removable without removing the stop from the tube.
21. In filling apparatus, a tube, a stop releasably secured on the tube, a projection releasably secured to the tube, and spacing 20 means between the stop and the projection, removable without removing the stop from the tube.
22. In filling apparatus, a tube, a stop on the tube, a projection secured to the tube, a 25 spring acting on the tube through the projection, and spacing means between the stop and the projection, removable without removing the stop from the tube.
23. In filling apparatus, a tube, a stop releasably secured to the tube and having a 30 socket, a projection secured to the tube, a spring acting on the tube through said projection, and a pin fitting in the socket in the stop, engaging the projection and being removable from the socket.
24. In filling apparatus, in combination 35 with a tube and means on said tube for determining the distance which the tube is inserted into a vessel, said means being adjustable with respect to the tube, a series of 40 different and interchangeable spacing elements adapted to engage with said adjustable means to hold it stationary in its various adjusted positions and removable without 45 removing said means from the tube.
25. In filling apparatus, in combination with a tube and means on said tube for determining the distance which the tube is inserted into a vessel, said means being adjustable with respect to the tube, means for 50 clamping the adjustable means to hold it stationary on the tube in its various adjusted positions, and a positively reinforcing spacing means to resist movement of the positioning means from its clamped position in 55 one direction, said spacing means being removable without removing said adjustable means from the tube.
26. In filling apparatus, in combination 60 with a tube and means on said tube for determining the distance which the tube is inserted into a vessel, said means being adjustable with respect to the tube, means for clamping the adjustable means to hold it stationary on the tube in its various adjusted 65 positions, and positively reinforcing spacing means to resist movement of the means from its clamped position in one direction, said spacing means comprising a series of different interchangeable spacing elements adapted to engage with said adjustable positioning means in its various adjusted positions, and removable without removing said adjustable means from the tube.
27. In filling apparatus, a tube, a stop to 70 be clamped on the tube in various positions therealong, positive resistive means on the tube, and a series of interchangeable spacing pins adapted to engage between the stop and the resistive means to reinforce the 75 clamping of the stop in its various adjusted positions, and removable without removing said stop from the tube.

In testimony whereof I have hereunto signed my name in the presence of two subscribing witnesses.

KARL KIEFER.
